NICOLAS HERZMARK, OF PARIS, FRANCE.

STARTING DEVICE FOR EXPLOSION-ENGINES.

1,366,180.

Specification of Letters Patent. Patented Jan. 18, 1921.

Application filed February 11, 1919. Serial No. 276,268.

To all whom it may concern:

Be it known that I, NICOLAS HERZMARK, a citizen of the Republic of France, and a resident of 11 Rue Labie, Paris, France, 5 have invented new and useful Improvements in a Starting Device for Explosion-Engines, of which the following is a specification.

The present invention relates to a starter for multiple cylinder explosion engines, and 10 is of a type comprising not only an indicator having a group of electric lamps corresponding to the different cylinders and indicating, through their several illuminations in sequence, the functioning of the several 15 cylinders as explosion cylinders, but also a distributor which serves to admit a charge of explosive mixture to one or more of the cylinders of the engine.

This distributor, according to the present 20 invention, permits a supply of explosive mixture to be sucked from the carbureter and to be then discharged simultaneously into the cylinder (or group of cylinders) functioning as the explosion cylinder in the 25 position in which the engine lies, and also into the cylinder (or cylinder group) functioning as the compression cylinder. The pistons in these cylinders are thus maintained in equilibrium up to the moment 30 when the ignition spark is flashed in the explosion cylinder (or cylinder group).

The present distributor comprises a pump cylinder rotatable around its axis to bring a pointer thereon opposite any one of the 35 group of indicator lamps for the cylinders of the engine. When brought to position opposite the lighted lamp which indicates the explosion cylinder, the distributor simultaneously establishes communication between 40 the pump chamber and carbureter passage, on the one hand, and on the other hand between the pump chamber and both the explosion cylinder (or cylinder group) and the compression cylinder (or cylinder group). The operation of the pump therefore 45 sucks a charge of explosive mixture from the carbureter and then discharges it simultaneously into both the explosion and compression cylinders (or cylinder groups).

The controlling hand-lever for the distributor actuates contacts which, when the hand-lever is brought from the position in which its pointer is opposite the lamp which is glowing, to its position of "dead point," 50 momentarily closes a high tension circuit

which causes ignition of the charge in the firing stroke cylinder (or cylinders of the set).

The annexed drawing and the following description relate to one form, by way of example, of carrying out the invention in its application to a four-cylinder engine.

Figures 1 and 1^a, placed end to end, show in axial section the pump-barrel with the indicating and distributing devices, the latter being in the position in which it is connected, for starting up purposes, with the cylinder of the motor in which the explosion stroke is occurring.

Figs. 2, 3 and 4 are cross sections in parallel planes on respectively lines 2—2, 3—3, 4—4 of Fig. 1.

Fig. 5 is a section on line 5—5 of Fig. 4.

Fig. 6 shows diagrammatically the connections of the indicator device.

Fig. 7 shows diagrammatically the connections of the circuit for the ignition of the charge of mixture forced into the cylinder in which the explosion stroke is taking place.

The distributor consists of a single-acting pump barrel *a* containing a piston *a*¹ which can be actuated from the exterior by means of a handle *a*²; this pump barrel ends at one of its extremities in a plug *b* having several 85 passages, exactly ground into the female portion or bush *c* of the distributor cock; at its other extremity the pump barrel *a* is fast with a handle *d* which enables the barrel to be turned about its axis *x*—*x* in its 90 cylindrical casing *a*³ and thus to bring passages hollowed out in the plug *b* opposite passages, formed in the thickness of the fixed bush *c* and communicating with the carbureter and the cylinder of the motor, 95 these different passages being suitably arranged in such a manner as to enable a charge of mixture from the carbureter to be drawn into the barrel of the pump and to force this charge into the cylinder which is 100 on the explosion stroke and the cylinder which is on the compression stroke in the position in which the motor has previously stopped.

In order to recognize in which cylinder 105 the explosion stroke is occurring, the following indicator device is utilized; (it is to be supposed that the order of firing of the cylinders 1, 2, 3, 4, is 1, 2, 4, 3.) In a collar *a*⁴ of insulating material fixed upon the cas- 110

ing a^3 concentrically with the pump-barrel a , are arranged four electric bulbs or lamps $i^1 i^2 i^3 i^4$ corresponding with the four cylinders 1, 2, 3, 4, and arranged in the order of 5 working of the latter: (see Fig. 6). These bulbs have all the same pole formed by a split ring g fitted in the insulating collar a^4 (Figs. 1 and 6). The other pole of each 10 of the bulbs is connected (Fig. 6) to a sector respectively $h^1 h^2 h^3 h^4$ and these sectors are insulated in the bottom of the cover of the distributor of the magneto secondary current. In the bottom of this same cover is also 15 located, concentrically with these sectors, a ring k directly connected to one of the poles of the battery h serving to light the bulbs $i^1 i^2 i^3 i^4$; contact is established between this ring k and that of the sectors $h^1 h^2 h^3 h^4$ corresponding with the cylinder 20 in which the explosion stroke is taking place, by a bridge or bar l , arranged, between the ring k and the sectors, upon the carbon-carrier of the distributor of the magneto and turning with the latter.

25 A ring j (Fig. 6), also mounted in the insulating collar a^4 in a plane parallel with and adjacent to that in which the split ring g is situated, is electrically connected to the other pole of the battery h . A contact in 30 the form of a bridge m , arranged exteriorly of the pump-barrel a between the rings g and j and turning with the pump-barrel a when the hand-lever d is actuated, enables contact to be established between the rings 35 g and j and consequently to complete the closing of the circuit for the lamp $i^1 i^2 i^3$ or i^4 for which contact has been established between the ring k and the corresponding sector, by the small bridge piece l arranged 40 on the carbon-carrier of the distributor of the magneto. This lamp which corresponds with the cylinder, the piston in which has stopped on the explosion or firing stroke, remains consequently incandescent for all 45 positions of the hand-lever d , which is caused to turn around the axis $x-x$, except when the hand-lever is brought opposite the split portion of the ring g ; this position will be hereafter termed "dead point position" and also corresponds with that for 50 which the plug b of the distributor, fast with this hand-lever d , has none of its passages opposite the passages in the bush c of the distributor-cock as will be hereinafter 55 explained. It is to be noted that the bulbs $i^1 i^2 i^3 i^4$ are also divided around the upper part of the insulating collar a^4 , these bulbs being situated at an angle of 72° one from another except the two extreme ones (i^3 and 60 i^4) which are separated by a double angle, being arranged each at 72° starting from the position of dead point of the hand-lever, that is to say, from line $o-o$ (Fig. 6).

In order to bring the plug b of the distributor into the position in which its pas-

70 sages allow suction of the mixture from the carburetor into the pump-barrel a and its forcing simultaneously into the firing-stroke cylinder and the compression-stroke cylinder, I make use of the following arrangement:—The bush c or fixed female portion of the distributor cock comprises, in a plane perpendicular to the axis $x-x$ (Figs. 1 and 2), a suction passage c^1 connected with the carburetor by a pipe (not shown) which 75 includes a non-return valve, which allows suction of the explosive mixture from the carburetor to take place into the pump-barrel a but prevents any forcing of the mixture into the carburetor; this passage c^1 is 80 situated in the vertical plane $o-o$ passing through the axis $x-x$, that is to say in the plane corresponding with the position of dead point of the hand-lever d . The plug b is fitted, in the same plane perpendicular to 85 the axis $x-x$ as the passage c^1 , with four passages b^1 which are separated one from the other by 72° except the two end passages which are at a double distance apart; when the hand-lever d is in the position of 90 dead point (as shown by dotted lines Fig. 2), none of the passages b^1 of the plug is opposite the suction passage c^1 in the bush.

The bush c is provided, in another plane perpendicular to its axis of rotation $x-x$ 95 (Figs. 1 and 4), with four passages c^2 connected to the cylinders of the motors c by pipes c^1 with non-return valves c^2 , permitting charging from the pump-barrel into these cylinders and preventing the return 100 of the mixture or the burnt gases into the pump-barrel. These four passages c^2 are exactly arranged in the same manner as the indicating bulbs $i^1 i^2 i^3 i^4$ in the insulating collar a^4 ; that is to say they are divided 105 at the upper part of the bush c at angles of 72° one from another except the two extreme ones which are divided by a double angle, each of 72° from the position of dead center, that is to say from the vertical plane 110 $o-o$ passing through the axis $x-x$. In the same plane perpendicular to the axis $x-x$ as the passages c^2 , there are formed, in the plug b , two passages b^2 forming between them an angle equal to that separating two 115 adjoining passages c^2 , that is to say 72° . When the hand-lever d is in the dead point position (as shown in Fig. 4), the plug b which is integral therewith, has neither of its two passages b^2 opposite a passage c^2 in 120 the bush; one of the passages b^2 is directed upwardly, in the vertical plane passing through the axis $x-x$, while the other passage is at 72° toward the left starting therefrom.

The two passages b^2 communicate between them and with the passages b^1 by a passage b^3 formed in the axis $x-x$ of the plug b which connects them with the interior of the pump-barrel a .

The motor being stopped, let us suppose that the hand-lever d is turned starting from its dead point position; one of the bulbs or lamps of the indicator will thereupon become incandescent; assume it to be the bulb i^3 . Thus the motor is stopped with the corresponding cylinder, viz. cylinder 3, ready for the explosion or firing stroke (by reason of the order of working 1, 2, 4, 3, of the cylinders, in cylinder 1, the compression stroke is taking place). It is sufficient to bring the pointer d^1 of the hand-lever d opposite this bulb i^3 which is incandescent, in order that the two passages c^2 of the bush corresponding with the cylinders 3 and 1 and that one of the passages b^1 of the plug should be located opposite the passage c^1 of the bush communicating with the carbureter. By bringing the pointer d^1 of the hand-lever d to the bulb i^3 , the plug b is turned by $(\frac{1}{10} + \frac{1}{5})$ of a turn toward the right, starting from the position shown in Figs. 2 and 4. Its two passages b^2 come opposite the passages c^2 connected with the cylinders 3 and 1, and a passage b^1 comes opposite the passage c^1 connected with the carbureter; it is sufficient then to pull out the handle a^2 of the piston a^1 in order to suck into the pump-barrel a suitable charge of mixture by means of $c^1 b^1 b^3$ and then to push back the piston a^1 in order to force this charge into the cylinders 3 and 1 by the passages $b^3 b^2 c^2$ and the corresponding pipes e^1 .

Suppose that in cylinder 1 the explosion stroke is taking place and the compression stroke in cylinder 2; by bringing the pointer d^1 of the hand-lever d to the bulb i^1 , the plug b has been turned by $\frac{1}{10}$ th of a turn toward the right starting from the position shown in Figs. 2 and 4, and suction can be effected through $c^1 b^1$ and forcing in of the charge through the two passages b^2 and the two passages c^2 corresponding with these cylinders.

If the bulb i^2 becomes incandescent, the cylinder 2 is ready for the explosion stroke and in the cylinder 4 the compression stroke is taking place; by bringing the pointer d^1 to this bulb i^2 , the plug is turned by $\frac{1}{10}$ th of a turn to the left, starting from the position shown in Figs. 2 and 4 and thus the necessary communications are obtained.

In order to load or charge simultaneously cylinder 4 (firing stroke) and cylinder 3 (compression stroke), if the plug b is turned $\frac{1}{10} + \frac{1}{5}$ of a revolution toward the left, starting from the position shown in Figs. 2 and 4, by bringing the pointer d^1 of the hand-lever to the lamp i^4 , a single one of the passages b^2 (Fig. 4) will be opposite passage c^2 corresponding with cylinder 4; in order to permit the charging of cylinder 3 (compression stroke), the following arrangement is utilized; the bush c comprises (Fig. 3) a supplementary pas-

sage c' in the same angular position as the passage c^2 corresponding with the cylinder 3 (that is to say at 72° toward the right, starting from the vertical plane $o-o$ passing through the axis $x-x$) but in a plane 70 perpendicular to the axis $x-x$ different from those of the passages c^2 or of the passage c^1 ; this passage c' is connected, in the thickness of the bush, with the charging passage c^2 corresponding with the cylinder 75 3 (Fig. 5). A supplementary passage b' is formed in the plug b in the same plane perpendicular to the axis $x-x$ as this passage c' but at 36° toward the left starting from the vertical plane $o-o$ passing 80 through the axis $x-x$ (Fig. 3). By causing the plug to turn to the extent of $\frac{1}{10} + \frac{1}{5}$ toward the left starting from the position shown in Figs. 2 and 3 and 4 (which has been automatically effected by bringing the 85 pointer d^1 of the hand-lever to the incandescent bulb i^4) the passage b' of the plug is brought opposite the passage c' of the bush, so that the forcing of the mixture into the cylinder 3 is effected from the 90 pump-barrel by the passages $b^3 b' c'$ and the passage c^2 corresponding with this cylinder, while the charging of cylinder 4 is effected directly by the corresponding passages $b^3 b^2 c^2$.

It is to be understood that this arrangement of the passages in the distributor cock has been given only by way of example (with a view to having to turn the plug through an angle as small as possible) but 100 there may be made in the arrangement any desired modifications enabling the same result to be obtained, that is to say the turning of the plug-passages relatively to the passages in the bush, in one position such that 105 suction of a charge of mixture from the carbureter can take place into the pump barrel and the forcing of such charge into the cylinders in which respectively the firing stroke and the compression stroke are 110 occurring, by a simple movement of the hand-lever d relatively to the indicating lamps.

In order to effect the ignition of the charge of mixture forced into the cylinders 115 for the firing stroke only, the following arrangement is employed:—in the insulating collar a^4 of the casing a^3 of the pump-barrel, are secured terminals or studs of small size in two pairs $n^1 n^2$ situated on each side of the 120 dead point of the hand-lever d (Figs. 1 and 7); in each pair, one of the terminals is connected as at n^1 through the magneto to the 125 sparking plugs of the cylinders while the other terminal is connected as at n^2 to a high tension coil (which might be replaced by a hand-operated magneto.) Opposite these pairs of terminals $n^1 n^2$ are two other pairs of terminals $p^1 p^2$, of low tension; in each pair one of the terminals is connected as 130

at p^1 to one of the poles of the battery h (Fig. 6), while the other terminal is connected as at p^2 to the low tension terminal of the coil, from which a conductor returns 5 to the other pole of the battery h . When the hand-lever d is brought back, from the position in which its pointer d^1 is opposite one of the indicating lamps, into its position of dead point, that is into the vertical plane 10 $o-o$, a small bridge q , arranged exteriorly on the pump barrel a and insulated therefrom, passes between one or the other of the pairs of terminals $p-p$ and thus closes the low tension circuit of the coil; the high tension current thus produced passes through a 15 small bridge piece r , arranged in an insulated manner on the pump-barrel a , between the pairs of terminals $n-n$ of the coil through the magneto to the sparking plug of the 20 firing-stroke cylinder. The division of the high tension conductor into two parts each connected to one pair of terminals $n-n$ (Fig. 25 7) enables the high tension current, coming from the magneto during the working of the engine, to be prevented from passing to the coil which serves for the ignition of the firing-stroke cylinder for starting up purposes.

The terminals $n-n$ and $p-p$ are arranged 30 toward the lower part at least 36° each side of the vertical plane $o-o$ corresponding to the position of dead point of the hand-lever d and they are besides very short so that the ignition circuit for the firing stroke 35 cylinder is not closed either when the hand-lever d is at its position of dead point or when the pointer d^1 of the lever d is opposite one or the other of the indicating lamps; it is only when the hand-lever is brought 40 back to its position of dead point, after having been brought with its pointer d^1 directed toward the lamp which is incandescent, that the bridges or contacts q and r pass between the pairs of terminals $n-n$ and 45 $p-p$, and that the circuit for the ignition of the firing stroke cylinder is closed during a very short time, sufficient for the spark to occur in this cylinder.

In order to start the motor it is sufficient:—(1) to move the hand-lever d from its dead point position $o-o$ until one of the indicating lamps is lighted; (2) to bring the pointer d^1 of the lever d opposite this lamp (the distributor is by the same action 55 brought into the position in which a charge of mixture can be drawn into the pump-barrel and forced into the firing-stroke cylinder and compression-stroke cylinder); (3) afterward to bring the hand-lever to its 60 position of dead point so that a spark passes at the sparking plug of the firing-stroke cylinder (the ignition circuit having been momentarily closed by the bridges or contacts q and r between the pairs of terminals

$p-p$ and $n-n$ by this movement of the hand-lever). The motor thus started immediately receives a new impulse by reason of the ignition of the charge forced by the distributor into the compression-stroke cylinder. 65

For the application of the invention to a 70 motor comprising groups of several cylinders working simultaneously with the same strokes, it is sufficient to connect each of the 75 passages c^2 to the cylinders of each corresponding group each indicating lamp corresponding to the different cylinders of each group.

In the following claims it is to be understood that where the context renders such a construction appropriate, the word "cylinder" is used in a sense broad enough to include a group of cylinders simultaneously functioning in the same manner in the engine cycle. 80

Having now particularly described and 85 ascertained the nature of my said invention and in what manner the same is to be performed, I declare that what I claim is:—

1. A starter for multi-cylinder explosion engines, comprising an indicator disclosing 90 the explosion cylinder of the engine, a rotatable pump casing having a pointer adapted to be brought into various predetermined positions with respect to the indicator, a valve associated with the pump casing and 95 moving therewith, a seat for said valve having an inlet passage for leading the explosive mixture to the pump and distributing passages leading from the pump to the several cylinders of the engine, said valve having passages communicating, in predetermined positions of the pump located by the indicator, with the inlet for the explosive mixture and the distributing passages leading to the explosion and compression cylinders of the engine. 100

2. In the construction specified in claim 1, the said indicator comprising a group of electric lamps corresponding in number with the cylinders of the engine, normally open 110 circuits therefor, and a contact device for closing the circuit of the lamp corresponding to the explosion cylinder.

3. In combination with the structure specified in claim 1, an ignition device for 115 each of the cylinders, and contacts associated with the pump casing automatically closing said ignition circuit in the explosion cylinder upon the rotation of the pump casing to the neutral or zero position of its 120 associated indicator.

In testimony whereof I have signed my name to this specification.

NICOLAS HERZMARK.
